SOAP DISH

Lester Morris, 135 Aspinwall St., Westbury, N.Y.

Filed May 23, 1960, Ser. No. 60,697

Term of patent 14 years

(Cl. D4—3)

FIG. 1.

FIG. 3.

FIG. 5.

3 → FIG. 2.

3 → FIG. 4.

FIG. 1 is a front perspective view of a soap dish embodying my new design;

FIG. 2 is a front elevational view thereof;

FIG. 3 is a vertical cross-sectional view thereof taken on line 3—3 of FIG. 2;

FIG. 4 is a top plan view thereof; and

FIG. 5 is a bottom plan view thereof.

The back of the soap dish is substantially plain.

The characteristic features of my design for the soap dish disclosed reside in the projecting sloped lip portion having upwardly curved ends and extending across the bottom of the front of the recess in combination with the soap supporting ribs which terminate short of the front edge of the bottom of the recess, as shown.

I claim:

The ornamental design for a soap dish, as shown and described.
